[57] CLAIM

The ornamental design for a cargo carrier, as shown and described.

DESCRIPTION

FIG. 1 is a perspective view of a first embodiment of a cargo carrier showing our new design including a cassette and compact disc carrier;

FIG. 2 is a front elevation view thereof;

FIG. 3 is a left side elevation view thereof;

FIG. 4 is a top plan view thereof;

FIG. 5 is a bottom plan view thereof;

FIG. 6 is a rear elevation view thereof;

FIG. 7 is a perspective view of a second embodiment of a cargo carrier showing our new design;

FIG. 8 is a front elevation view thereof; and,

FIG. 9 is a top elevation view thereof.

The right elevation view of the first embodiment of FIG. 1 is similar to the left side elevation view shown in FIG. 3. The left elevation view of the second embodiment of FIG. 7 is similar to the left elevation view shown in FIG. 3. The right elevation view of the second embodiment of FIG. 7 is similar to the left elevation view shown in FIG. 3. The bottom plan view of the second embodiment of FIG. 7 is similar to the bottom plan view shown in FIG. 5. The rear elevation view of the second embodiment of FIG. 7 is similar to the rear elevation view shown in FIG. 6.
